UNITED STATES PATENT OFFICE.

CLIFTON CHISHOLM, OF CLEVELAND, OHIO, ASSIGNOR TO THE AMERICAN MULTIGRAPH COMPANY, OF CLEVELAND, OHIO, A CORPORATION OF OHIO.

ASSEMBLED PRINTING FORM.

Application filed April 18, 1921. Serial No. 462,250.

To all whom it may concern:

Be it known that I, CLIFTON CHISHOLM, a citizen of the United States, residing at Cleveland, in the county of Cuyahoga and State of Ohio, have invented a certain new and useful Improvement in Assembled Printing Forms, of which the following is a full, clear, and exact description, reference being had to the accompanying drawings.

This invention relates to assembled printing forms wherein the characters are pressed or embossed on strips removably held on a suitable holder. The invention is well adapted for embodiment in address plates, comprising holding plates having means for mounting address printing members thereon, or it may be embodied in a page printing form.

One of the objects of the invention is to provide novel means to hold the impression member upon a holder.

A further object of the invention is to provide in a plate holder, a novel form of fastening means, adapted to secure a strip bearing impression characters, upon the plate holder.

An additional object of the invention is to provide an address plate with projecting, alternately arranged, series of tongues which are adapted to co-operate with an impression member to hold it upon the plate holder.

A further object of the invention is to provide a plate holder having a number of sets of alternately extending tongues, the alternate tongues serving to co-operate with a plurality of address printing impression strips to hold the latter in place.

Other objects of the invention are to provide a novel type of impression member and suitable means for holding it.

Additional objects of the invention will be apparent from the following specification taken in connection with the accompanying drawings, wherein Fig. 1 is a plan of an address plate holder constructed according to my invention; Figs. 2, 3, 4, and 5, are sectional views taken on lines 2-2, 3-3, 4-4, and 5-5, respectively, in Fig. 1. Fig. 6 is a section of a character strip on an enlarged scale. Fig. 7 is a view similar to that of Fig. 1, showing the impression members and identification card mounted upon the address member; Fig. 8 is a side eleva-

tion of the plate holder; Fig. 9 is an end view of the plate holder; Fig. 10 is a bottom plan view of the plate holder; Fig. 11 is a perspective view of one of the impression strips; Figs. 12, 13 and 14 are plans of an address plate with various arrangements of multiple line printing members, illustrating the adaptability of this invention to various requirements; Fig. 15 is an elevation showing my invention applied to a cylindrical printing member; Fig. 16 is an end elevation of the cylindrical printing member; Fig. 17 is a fragmentary section thereof.

Referring to the drawings by reference characters, I have shown at 10 a plate holder which may have the general shape of the holder shown in my prior application Serial No. 410,710, filed September 16, 1920. The plate holder may be made from a single sheet of metal and may comprise a body portion 11 having folded-over upper and lower portions 12 and 13. The ends of the plate holder are shown as bent to form rails 15 which serve to strengthen the holder and to space the address plates when stacked. Portions of the plate above the rails are indented as at 16 to provide notches into which wheels carried by the inking rollers drop to bring the inking roll into contact with the printing characters on the plate.

The plate is shown as provided with a number of struck up lugs 19 consisting of loops punched from the body of the plate. Suitable index members (not shown) may be fitted into these loops. Tongues 21 stamped from the body of the plate holder are shown as co-operating with the folded portion 12 to hold an identifying card 22 in place. An up struck spring tongue 23, and a stop 24 may serve to prevent longitudinal movement of the identifying card. The plate may be apertured at 27 so that the finger or a pencil or other object may be used to aid in removing the identifying card.

A plurality of projections 30 are provided on the plate holder. These projections may be struck from the body of the plate holder, and are shown as having their edges spaced from the plane of the body thereof. The projections are arranged in parallel rows with the projections in one row directed in an opposite direction from those in an adjacent row, for a purpose to be presently described.

The projections, shown on an enlarged scale in Fig. 3, may be sheared along three sides from the body portion of the plate, and may be curved, as at 31, to present a portion 32 disposed above and substantially parallel with the face of the plate. It will be noted that the base of the oppositely facing projections at each row overlap, as shown at 33. The arrangement is such that each pair of alternately disposed projections provides a pair of oppositely facing channels 34 which may extend longitudinally of the plate, or transversely, if desired. Four sets of these pairs of rows of projections are indicated in Fig. 1, although, if desired, other arrangements may be provided.

In Fig. 11, I have shown a strip 40 of metal or other suitable material having printing characters 41 thereon. The printing characters may be embossed upon the strip or may be otherwise provided as desired. In the enlarged cross sectional view of the strip as shown in Fig. 7, it will be noted that the lateral edges of the strip are bent as at 42 to form holding flanges. These flanges may consist of a series of projections or they may be continuous as shown. The opposite edges of the strip 43 are smooth and lie in a plane substantially parallel to that of the face of the strip. The angle A between the strip and the flange is acute. The inner face 44 of the flange is substantially plane while the outer edge is somewhat curved, as at 45. It will be noted that the band joining the flange with the body of the strip is rather sharply defined.

In use, the flanges on the character strip are adapted to engage the flanges of a set of projections 32, as shown in section at B, Fig. 3. It will be noted in this figure that the rear face of the character strip lies parallel to the front face of the struck-up projections and that the flanges on the strip extend beneath the projections.

The printing strips are held in position by the resiliency of the flanges 42 and the projections 30. The parts are designed so that the impression strips will have the slight binding action upon their retaining projections to prevent their becoming accidentally displaced in use. In using the plate holder constructed according to my invention, the strip properly embossed with the desired characters, is arranged adjacent the end of a pair of projections 30 and is then slid along the plate until its proper position is reached. Sufficient space is provided between the contiguous printing strips so that they may readily slide by one another. Suitable stops shown as up struck tongues 50 may be provided to limit the movement of the strip in one direction.

The plate holder shown in Fig. 7 is indicated as provided with four printing strips, 65 one for the name, the second for the street

and number, the third for the city and the fourth for the State. In some cases, as for example in public service corporations, such as gas companies, the street and number, city and State need not be changed but may be constant, and it may be desired only to change the name, as for instance when different parties occupy the same residence. A device fulfilling these requirements is shown in Fig. 12 wherein a single line strip 70 supplies the name and a multiple line strip 71 prints the other three designations.

In another instance it might be desirable to employ a wide strip 74, Fig. 13, say two lines wide carrying the city and state designation, together with some other indicia 75, while elsewhere on the address plate the name and address might be supplied by line characters, while another designation covering more than the single printing line 75 may be used, as at 77.

In a different case, it might be desired to have the city and state carried on one printing strip, as 80, Fig. 14, with the name and address supplied by individual strips, and in connection with such an arrangement, it might be desired to provide a printing member sufficiently wide to extend the full effective printing width of the character as shown at 81.

The various arrangements of printing members are merely illustrative of the wide adaptability of my device, and are not intended to be restrictive.

I have found that my invention is well adapted to printing machines, wherein rotating cylinders are provided. In Figs. 15, 16 and 17, I have shown a modified form of my invention wherein a flexible metal strip 60 is shown as mounted upon a printing drum 61. One end of this strip may be attached to the printing drum by screws 62, while the other end may be provided with apertures adapted to fit over other screws 62, the arrangement being such that the metal strip may be readily detached.

The strip 60 may be provided with rows of projections 63, which are adapted to receive character strips 64. The projections and the character strips may be similar to those previously described, and the projections may be arranged so that the printing strips extend either parallel to the axis of the roller, or around the roller, or a combination of strips, some of which run around the cylinder and some of which run longitudinally thereof, may be provided. The printing drum shown in Fig. 15 may be used to print circular letters, or for various other purposes, and, if desired, it may be used in connection with a machine having address plates which supply the proper heading to the letter.

From the foregoing description, it will be apparent that I have devised a simple

and efficient printing form, which can be cheaply made, and which is adaptable to a great many different uses.

Having thus described my invention, I 5 claim:

1. A printing member comprising an embossed strip having flanges bent inwardly behind the strip, and a holder having projections which the strip overlies with its flanges 10 extending behind the projections.
2. The combination of a holder having a plurality of projections thereon, and a removable impression member overlying said projections.
- 15 3. In a printing device, a body portion having two rows of projections thereon, the projections in adjacent rows facing in opposite directions, and their bases overlapping.
- 20 4. A printing strip holder made of sheet metal and having a plurality of projections thereon, said projections having their extreme portions spaced from and parallel to said sheet.
- 25 5. The combination of a holder having a plurality of projections spaced thereabove, and an impression holder member overlying and secured upon the projections.
- 30 6. The combination of a holder having a plurality of oppositely directed retaining projections, and an impression member overlying said projections and flanged to extend beneath them.
- 35 7. In combination, a holder having a plurality of retaining projections, said projections being staggered and alternately directed in pairs, and an impression member secured to and overlying said projections.
- 40 8. A printing device comprising a printing strip holder having a plurality of retaining projections thereon, said projections being alternately directed in pairs, and a printing member engaging the pairs of alternately directed projections.
- 45 9. A holder having a plurality of rows of alternately facing projections thereon and lying thereabove parallel to the body of the holder and connected to the holder by curved portions, and an impression member extending over said projections and having a portion extending beneath the projections.
- 50 10. The combination with flanged printing strips, of a holder having a plurality of overhanging projections thereon, said projections being arranged parallel to the holder and the strip flange extending beneath them.

- 55 11. The combination of a holder having a plurality of projections each with a portion arranged substantially parallel to the body of the holder and spaced therefrom, and an impression member overlying said projections and secured by having portions extending behind the said portions of the holder.

12. A printing strip holder having projections thereon, the projections being arranged in rows parallel to the end edges and to the side edges of the holder, the projections in each row facing in opposite direction to those in an adjoining row. 65

13. An impression strip comprising a body portion having edge flanges extending at an angle to the body portion and directed toward each other, and a holder having projections behind which said flanges extend. 70 75

14. The combination of a holder having a row of struck-up projections thereon, and a printing strip adapted to overlie said row and having edge flanges extending behind edges of the projections overlain. 80

15. A holder made of sheet metal and having a row of projections struck up therefrom and an embossed printing strip adapted to overlie said projections and having edge flanges to extend beneath them, and said strips being of different widths and adapted to be interchangeably mounted on the holder by straddling a different number of rows of projections. 85

16. A device having a plurality of rows of projections, and printing strips held thereby, said strips being of different widths and adapted to be interchangeably mounted on said device. 90

17. The combination with a holder having a plurality of rows of projections and printing strips of different widths and each provided with flanged edges, one of said strips straddling one row of projections and another of said strips straddling a plurality of 100 rows of said projections. 95

18. A holder having a plurality of rows of projections struck up therefrom, and a plurality of embossed strips, said strips being adapted to overlie projections and having edge flanges to extend beneath them and said strips being of different widths and adapted to be interchangeably mounted on the holder by straddling a different number of rows of projections. 105

19. A holder having a plurality of rows of raised projections thereon, and printing strips of different widths mounted thereon, the narrower strips engaging oppositely extending edges of projections in one row and 115 projecting edges of projections in different rows.

20. The combination of a holder having a plurality of rows of struck up projections thereon, and a printing strip adapted to 120 overlie a plurality of rows and having edge flanges extending behind the distant edges of projections overlain.

21. The combination with an address plate holder having means for holding wide and 125 narrow printing strips, and an assembled form thereon comprising a wide strip and a plurality of narrower strips aligned there-

with, the wide strip having a width equal to that of the narrower strips plus the idle space between them.

22. An address plate holder having a plurality of rows of struck up projections thereon and a printing form mounted on said plate comprising narrow strips embracing a single row and wider strips embracing a plurality of rows of such projections.

10 23. A holder having a plurality of rows of projections, and a printing strip wide enough to lie over a plurality of rows of projections and having edge flanges adapted to engage the distant edges of the projections overlain.

15 24. An address holder comprising a plate having a plurality of parallel rows of struck up projections thereon, and embossed printing members of different width, held thereon by overlying projections and extending behind them, the wider strips extending over more rows of projections than the narrow ones.

25 25. The combination of a holder having a plurality of equidistant rows of projections provided with tongues which extend in opposite directions, and a plurality of printing members of different widths adapted to overlie a different number of rows of projections, 30 said printing members having converging edge flanges adapted to extend behind the distant edges of projections.

35 26. A holder having a plurality of equidistant rows of projections on the face thereof and a plurality of printing members of different widths adapted to be interchangeably mounted thereon, the wider members having a width equal to that of a plurality of narrower members plus the space between

adjacent members when mounted on the 40 holder.

27. The combination of a holder having a plurality of equi-distant rows of projections provided with tongues which extend in opposite directions, and a plurality of printing members adapted to overlie adjacent rows of projections and extend behind them, 45 said rows being so spaced that adjacent printing members are out of contact with each other.

50 28. The holder comprising a plate having a plurality of parallel rows of struck-up projections thereon, and embossed printing strips held thereon by overlying the projections and extending behind them.

55 29. The combination of a plurality of sheet metal printing members each comprising an embossed strip having edge flanges, and means for holding such strips parallel with their adjacent flanges out of contact 60 with each other.

65 30. The combination of a plate holder having a turned down marginal edge, a plurality of tongues struck from said plate holder parallel to said turned down edge, an identification card adapted to be held by said turned down edge and tongues, additional tongues adapted to prevent lateral displacement of said identification card, said plate holder being apertured to facilitate the removal of said identification card and a plurality of indexed tab holding loops in the body of the plate holder adjacent the aperture.

70 75 In testimony whereof, I hereunto affix my signature.

CLIFTON CHISHOLM.
